US0D1066272S

(12) **United States Design Patent** (10) **Patent No.:** **US D1,066,272 S**
(45) **Date of Patent:** ** *Mar. 11, 2025

(54) **CONTROL AID HOUSING**

- (71) Applicant: **View, Inc.**, Milpitas, CA (US)
- (72) Inventors: **Rao P. Mulpuri**, Saratoga, CA (US); **Nitesh Trikha**, Pleasanton, CA (US); **Nayana Vasant Ghantiwala**, San Jose, CA (US); **Jue Wang**, San Jose, CA (US); **Anurag Gupta**, San Jose, CA (US); **Christopher La Fontaine Whittall**, Los Gatos, CA (US); **Jonathan Ambat Corpuz**, Fremont, CA (US); **Timothy Scott Hibbard**, Menlo Park, CA (US)
- (73) Assignee: **View Operating Corporation**, San Jose, CA (US)
- (*) Notice: This patent is subject to a terminal disclaimer.
- (**) Term: **15 Years**
- (21) Appl. No.: **29/875,952**
- (22) Filed: **May 12, 2023**

CLAIM

The ornamental design of a control aid housing as shown and described.

DESCRIPTION

FIG. 1 is a front view of the control aid housing.

FIG. 2 is a rear view thereof.

FIG. 3 is an isometric view thereof.

FIG. 4 is a left side view thereof.

FIG. 5 is a right side view thereof.

FIG. 6 is a bottom view thereof; and,

FIG. 7 is a top view thereof.

The broken lines in the drawings depict portions of the control aid housing that form no part of the claimed design. The dash-dot-dash broken define bounds of the claimed design and form no part thereof.

1 Claim, 5 Drawing Sheets
